UNITED STATES PATENT OFFICE.

ORVIL G. LEMMER, OF SEATTLE, WASHINGTON.

TRUNK.

1,363,134.

Specification of Letters Patent. Patented Dec. 21, 1920.

Application filed November 10, 1919. Serial No. 336,872.

To all whom it may concern:

Be it known that I, ORVIL G. LEMMER, a citizen of the United States, residing at Seattle, in the county of King and State of Washington, have invented a new and useful Trunk, of which the following is a specification.

My invention relates to improvements in trunks, particularly those of the wardrobe variety, and is an improvement over the trunk for which U. S. Patent #1,292,490 was issued to me on January 28th, 1919. Its object is to provide a trunk, simple in construction, which will combine the benefits 15 of a wardrobe trunk and a compartment trunk.

These and other features of the invention will be described in connection with the drawings and pointed out in the appended 20 claims.

In the drawing, in which like reference characters indicate like parts, Figure 1 is a top view of the trunk with the front and side lids open. Fig. 2 is a plan view of the 25 upper portion of the trunk, when standing on end, particularly illustrating the arms which carry clothes hangers, and the members supporting said arms. Fig. 3 is a plan view of one of said arms, with clothes-hanging devices. Fig. 4 is a vertical sectional view of the removable wardrobe section, taken through the side. Fig. 5 is a vertical sectional view of the removable wardrobe section, taken through the front, showing 30 extended the support for the arms which carry clothes-hanging devices, said arms and clothes hangers, for the purposes of this illustration, being removed. Fig. 6 is a front view of the trunk, when standing on 35 end, showing the lids open, the wardrobe section removed, and two removable shelves inserted in lieu of the wardrobe section.

The body of the trunk is designated by 1, the front lid by 2, and the side lid by 3. 4 40 represents a member adapted to carry the arms which support the clothes-hanging devices. Assuming that the trunk is standing on one end, this member is located near the top of the removable wardrobe section, is 45 fastened to the back end wall of said section and spaced out therefrom by a suitable fixture. Pivottally connected to this member is another member 5 of practically the same size and form. These two members, comprising the support for the arms, are pro-

vided with and connected by a longitudinal slot illustrated by 6. The pivotal connection at 7 permits the member 5 to be extended in the same plane as member 4, as shown in Figs. 2 and 5, or to be brought forwardly 60 so as to be contained within the body of the trunk and of the wardrobe section. Suitable means are provided, adjacent the top portions and the pivotal connection between members 4 and 5 for maintaining said members and their longitudinal slots in alignment, when said member 5 is extended as shown in Figs. 2 and 5. Slidably connected with these arm supporting members is a series of arms carrying clothes-supporting 65 devices. Fig. 3 is a side plan view of one of the same. The fixtures 9, fastened to the arm by the rod 10, or in any other suitable manner so as to permit a forward or rearward movement, slidably engage the longitudinal slots 6 of the members 4 and 5, so that when the trunk is closed the arms carrying the clothes supporting devices can be slid 70 close together and be within the body of the wardrobe section. When the trunk is open, and the member 5 extended in a plane with member 4, said arms, operating in said slots, can be slidably extended over the members 4 and 5, giving ready access to the clothes. 75 Connected with the arms, and spaced slightly 80 away therefrom, are the two flat oppositely located members 11. These members are movable, but they have a sufficiently frictional contact at their connection with the arms so as to remain in any position to 85 which they may be placed, and adapted to hold articles of apparel. In the drawing, Fig. 3, they are shown as extending downwardly, but when in operative position they 90 would be usually located approximately as shown by the dotted lines in Fig. 3. Connected with said arm, shown in Fig. 3, is a 95 clothes hanger 12, of suitable form.

In Fig. 4 is shown the clothes-retaining gate in operative position. 13 illustrates the body, of rigid construction. Located on one outer side and near the top and bottom portions of the gate is a pair of gate-supporting members having offset arms 14, with downwardly extending offset toes 15. On the 100 other outer side of the gate is an offset arm 16, having an upwardly extending toe 17. Attached to the rear wall of the wardrobe section are a pair of cleats 18, provided on their upper portions with a plurality of slots 105 110

extending transversely and open at the ends adjacent the interior portion of the section, indicated by 19. The offset toes 15 are adapted to fit into these slots, allowing an adjustment of the gate either forward or rearward, and also to permit the gate to swing forward or backward. Said slots are open at the ends, as indicated, to permit the removal and adjustment of the gate, however, at the other ends of said slots and directly underneath thereof, said cleats are provided with additional openings adapted to hold said toes 15 in place, permit pivotal movement thereof, and also retain said gate in adjusted position. Attached to the side wall of the wardrobe section is the support 20, Fig. 5, to which is pivotally connected the arm 21, having in its upper portion, and for the greater part of its length, a plurality of small openings, in any one of which the upwardly extending toe 17—the toe and its arm being of spring material—can engage, for the purpose of retaining the gate in any adjusted position. The arm 21, being bolted to the fixture 20, by bolt 22, can be extended downwardly and out of the way of the clothes when desirable to remove them from the wardrobe section.

The body of the removable wardrobe section is provided with a plurality of rollers 23, mounted on ball bearings, to facilitate the movement of the wardrobe section. These rollers are concave circumferentially, they are located at the upper and lower portions of the side wall of the wardrobe section and revolve on the tracks 24, and within the limits of the retaining members which extend the depth of the wardrobe compartment of the trunk and located at the top and bottom portions thereof, as shown at 25, in Fig. 6. The lower member 25 operates in a slot in the bottom portion of the wardrobe section, and the upper member 25 serves as a retaining medium against the upper and inner edge of said wardrobe section. At 26, inside of the wardrobe compartment and adjacent the top outer edge thereof is a spring bolt, adapted to engage the projection 27 on the removable wardrobe section, to retain said section, if desired, within the wardrobe compartment, and at the same time permit the wardrobe section to be extended for nearly its full depth, so that the clothes may be easily accessible. If it is desired to remove the wardrobe section entirely from the wardrobe compartment, this is effected by disengaging the spring bolt 26 from the projection 27. Located at the lower portion of the removable wardrobe section, as shown at 28, Fig. 5, is a pocket made of flexible material adapted to hold two partitions for the wardrobe compartment. Should the user desire to utilize the trunk without the wardrobe section, it can be removed, and these partitions or shelves in-

serted in the wardrobe compartment, in grooves provided therein, as is shown at 29 in Fig. 6.

In order that the construction of the body of the removable wardrobe section may be more readily understood, I will state that it has a back and bottom sections, and one side section, said side section lying adjacent to the central partition of the trunk when in operative position and inclosed in the trunk; the front, top and the other side of the removable wardrobe section are open, to facilitate the handling or inspection of the clothes. 30 designates the drawer section, which comprises a plurality of drawers 31 slidably mounted on horizontal supports on the sides of the drawer compartment. 31 illustrates the lock, located on the side lid 3.

In using the trunk, the wardrobe section is rolled out from the body of the trunk for approximately its full length and retained in this position by the spring bolt 26 and the catch 27; the supporting member 5 for the arms is then extended in the plane of the supporting member 4, bringing the longitudinal slots in alinement, means are then applied for holding said supporting members in this position. The arms carrying the clothes-hanging devices can then be moved to any portion of the length of said members by means of the longitudinal slot extending through and between them and the fixtures 9, located at the rear ends of the arms and operating in said slots.

In the patent granted to me, hereinbefore referred to, the device for supporting the clothes-carrying arms was of lazy tongs construction, one end of which it was necessary to fasten to the lid of the trunk when said device was extended. The present device is simpler and stronger in construction and is self-contained within the wardrobe section, in that when the member 5 is extended it is completely operative in itself and will support the arms, the hangers and the clothes without the need of any additional support. When the wardrobe section is entirely removed from the trunk, under the present construction, the arm carrying device will still perform its functions completely, permitting light and air to get to the clothes and making them readily accessible. The roller bearings of the wardrobe section, operating on the small tracks as indicated, make it easier to extend said section from or return it to its compartment.

The clothes-retaining gate presents the feature, that while it is adjustable to different depths, it is adapted to swing inwardly or outwardly, and the clothes can be removed from the section without having to demount the gate.

The lids on this trunk are so hung, that the trunk can be placed on end in a corner,

opened and used in its entirety, with the front lid flat against the wall, thus effecting great economy in space. As the lock is located on the smaller or side lid, the trunk 5 can be packed and locked ready for travel without changing it from its position in the corner, a great convenience in packing.

The auxiliary clothes-hanging fixtures 11, in connection with the arms, enlarge the 10 clothes-carrying capacity of said arms, and as they are of flat construction, do so without a sacrifice of space.

The pocket for carrying the extra partitions, and the means for applying said partitions when the wardrobe section is 15 entirely removed from the trunk, as heretofore described, add to the usefulness of the trunk.

I claim:

20 1. A removable wardrobe section for a trunk, having in combination a body member substantially rectangular in form, open at the front, top and one side, a member adapted to carry arms for holding clothes- 25 retaining fixtures, comprising a support attached to the back and side portions and adjacent to the top of said body member, and spaced away from the back thereof, said support having a centrally located longitudinal slot, another support pivotally connected therewith also having a centrally located longitudinal slot adapted to align with said first slot, means for holding said supports in the same plane when said second 30 support is extended and so aligned, a plurality of arms for carrying clothes-retaining fixtures each having, in connection with a pintle extending transversely through the

shoulder of the arm, at the upper edges of said shoulder, a member comprising a vertically disposed body portion, oppositely bent laterally extending lips on the extremities of said body portion, the lower lip terminating in a right angular upstanding section, at the lower edges of said shoulder a 40 member comprising a vertically disposed body portion, oppositely bent laterally extending lips on the extremities of said body portion, the upper lip terminating in a right angular downstanding section, said last 45 50 named members adapted to slidably and detachably engage said slots.

2. In a trunk, in combination with a removable wardrobe section thereof, a clothes-retaining gate comprising a rigid body 55 member having at one side and hingedly mounted thereto a pair of offset arms each carrying a downwardly extending foot, at the other side of said gate, a spring offset arm with an upstanding foot, attached to 60 the back wall of said wardrobe section a pair of cleats in vertical spaced relation carrying at their top portions a plurality of slots open at the ends adjacent the gate, said slots adapted to hold said downwardly 65 extending feet in adjusted position and said feet to pivotally engage said slots, attached to the side wall of said wardrobe section, and adjacent the front edge, a member on which is pivotally mounted a transversely 70 extending arm having a plurality of openings adjacent its upper edge adapted to receive and hold the upstanding foot of said spring offset arm.

ORVIL G. LEMMER.
